United States Patent

Des. 237,446
Patented Nov. 4, 1975

237,446

IMPLEMENT HOLDER

Harold P. Ashton, Providence, R.I., assignor to
Dart Industries Inc., Los Angeles, Calif.

Filed July 25, 1974, Ser. No. 491,889

Term of patent 14 years

Int. Cl. D7—06

U.S. Cl. D7—73

FIG. 1

FIG. 2

FIG. 3

FIG. 4

FIG. 5

FIG. 6

FIG. 1 is a top plan view of an implement holder showing my new design;

FIG. 2 is a front elevational view thereof;

FIG. 3 is a bottom elevational view thereof;

FIG. 4 is a top elevational view thereof;

FIG. 5 is a bottom plan view thereof; and

FIG. 6 is a rear elevational view thereof.

I claim:

The ornamental design for an implement holder, substantially as shown.
